COSMETIC APPLICATOR

Blakely A. Wagner, Los Angeles, Calif.

Application August 13, 1945, Serial No. 610,597

10 Claims. (Cl. 15—185)

1

My invention relates to cosmetic applicators and more particularly to applicators of the class having in combination a reservoir or container for the cosmetic and an instrument for applying the cosmetic to the lips, skin, nails, or other parts to be so treated.

It is desirable in such an applicator to have the brush or similar instrument receivable within the body of the device so that it may be kept clean and will not stain the interior of a handbag or pocket book. It is also desirable to have the brush attached to the body of the device so that it will not be lost, and in such manner that it will not come in contact with a table-top when the applicator is placed thereon in open position. As the user may wish to use cosmetics of various colors for different occasions, the reservoir or magazine portion of the applicator is preferably easily removable and replaceable in duplicate, as is the brush portion of the device.

It is accordingly a principal object of my invention to provide a cosmetic applicator in which the brush or similar instrument is supported by a member which may be telescoped within the handle of the applicator.

It is a further object to provide means for reversing the position of the brush in relation to its supporting member and to the handle so that the brush end enters the handle at the beginning of the inward telescoping movement 30 and the other end of the supporting or telescoping member forms a closure for the handle.

It is still another object of my invention to provide supporting and guiding means for the brush to maintain it in axial alignment with the handle when in extended position so that it will withstand lateral pressure without guidance by the fingers and will not sag against a table-top when laid thereon.

Another object is to connect the brush and the telescoping member and the handle to one another in such manner that the reversing and telescoping action may be easily accomplished and yet the parts not detached and lost.

A further object of my invention is to provide 45 a cosmetic applicator having a handle to which magazines of the cosmetic material may be easily attached and may be discarded when expended or when a change of cosmetic is desired.

These and other objects of my invention will become apparent from the following description of a preferred form thereof and by reference to the accompanying drawings illustrating that form, in which:

Figure 1 is a perspective view of my cosmetic 55

2

applicator in closed position as it would be carried in a pocket book;

Figure 2 is a perspective view with the brush supporting member withdrawn from the handle into which it telescopes but with the brush and brush shank not yet extended to usable position;

Figure 3 is a longitudinal section with parts shown in elevation, on an enlarged scale, showing the telescoping member withdrawn from the handle, and the brush shank extended;

Figure 4 is a view similar to Fig. 3, with the telescoping member re-entered into the handle, and the handle turned so as to engage and hold the telescoping member and the brush shank 15 ready for use;

Figure 5 is a transverse section taken on the line 5—5 of Fig. 3 illustrating the engagement of the telescoping member with the handle when the former is withdrawn from the latter;

Figure 6 is another transverse section taken on the line 6—6 of Fig. 4, showing the telescoping member pushed back into the handle, and the handle turned to engage and hold it;

Figure 7 is a transverse section on the line 7—7 of Fig. 3, illustrating the engagement of the cosmetic magazine with the handle;

Figure 8 is a perspective view of the cosmetic magazine detached from the handle; and

Figure 9 is a perspective view of the cosmetic magazine with a cap attached as it would be carried as a replacement.

Referring now to the drawings in detail, my cosmetic applicator will be seen to comprise four principal parts which are a handle 10, a telescoping supporting member 11, a pivoted instrument holder 12, and a cosmetic magazine 13. The handle 10 is preferably a cylinder of uniform bore in its central portion, and of exterior diameter expanding rearwardly to make a smooth engagement with the magazine 13. The telescoping member 11 is bifurcated, the forks 14 joining at their inner ends in a head 15 which fits slidably in the bore of the handle 10. The forks 14 are in cylindrical extension of the head 15, but flattened on their outer sides, and of course similarly flattened on the perpendicular diameter by the cutting away of the groove between them, so that only on their diagonal diameters do they come in contact with the bore of the handle 10. However, this long contact of the forks 14 on their diagonal diameters, in addition to the length of the head 15, maintains the telescoping member in easy slidable alignment within the handle 10. The flattening of the sides of the forks 14 is extended partly along the head 15 to form flats 16

thereon. A pair of keys or lugs 17 within the bore of the handle 10 engage the flattened sides of the forks 14 and prevent rotation of the brush support 11 when the support is partly withdrawn from the handle, and by engagement with the shoulders of the flats 16 prevent complete withdrawal of the brush support from the handle.

Forks 14 are provided with keyways 18, as shown in dotted lines in Fig. 6, the keyway of one fork being diametrically opposite the keyway of the other fork. When the member 11 is telescoped to the fullest extent into the handle 10, as shown in Fig. 4, the keyways 18 are in annular register with the keys 17, permitting rotation of the member 11 within the handle, and a twist of either of these members relatively to the other will cause the keys to engage in the keyways and thereby lock the member 11 in the inwardly telescoped position. The keyways are eccentrically grooved to have increasing radius from the axis of the member 11, so that a slight degrees of twist, sufficient to effect the above mentioned lock, will also wedge the keys against the bottom of the keyways and hold the member 11 in its locked position by friction. This locking and wedging action is, of course, as possible when the parts are in the position shown in Fig. 1 as in the more illustrative view of Fig. 4.

At their forward ends, the forks 14 are each expanded into portions 19 of elongated spade shape, the increased thickness of these portions providing support for a pivot pin 20, connecting them, and their rearward shoulders abutting smoothly against the forward end of the handle 10 when the telescoping member 11 is fully entered therein and limiting such telescopic movement. The instrument holder 12 is pivotally mounted on the pivot pin 20 between the forks 14, with a portion 22 similar in shape to and lying between the portions 19 of the forks but having a more elongated nose 23, and a removable shank 24 on the side of the pivot opposite to the nose 23. The shank 24 is tipped with a brush 24a or other instrument suitable to the cosmetic to be used. When the shank 24 is placed between the forks 14, as in Fig. 2, in readiness to be telescoped into the handle 19, the portion 22 conforms with the portions 19, except for the elongation of the nose 23, and assists in making a smooth juncture with the handle 10. When the nose 23 is placed between the forks 14 and the member 11 is telescoped into the handle 10 until the shoulders of portions 19 abut the end of the handle, the nose 23 extends inwardly between the keys 17, and to permit the relative twisting of the member 11 and the handle 10, it is provided with keyways 25 in diametrically opposed shoulders which then lie in extension of the keyways 18. The keys 17, as shown in Fig. 6, need not engage the bottom of the keyways 25 with frictional pressure as they do the keyways 18, but should have little clearance therewith so as to hold the shank 24 in substantially rigid outward extension, to keep the instrument tip from sagging against a table top or other supporting surface.

It is desirable, for sanitation and cleanliness, always to pivot the instrument holder 12 by means of the nose 23 and to avoid grasping the shank 24 to align the nose 23 with the forks 14. To obviate the need of holding the shank 24 when the applicator is in the position of Fig. 3 and about to be telescoped to the position of Fig. 4, at least one of the expanded portions 19 is provided on its interior face with a semi-circular groove 26 in which is guided a pin 27 carried by

the instrument holder 12. The engagement of the pin with either end of the groove limits the pivotal motion of the instrument holder to positions in which the shank 24 is either extended directly outwardly, or aligned with and between the forks 14.

The cosmetic magazine 13 is preferably provided with a flat base to permit it to stand in a vertical position, and is attached to the handle 10 by means similar to those locking and wedging the member 11. The magazine has a forwardly facing shoulder 28 which abuts against the handle 10 in a smooth juncture. Extending forwardly from the shoulder 28 so as to enter the opening at the rear end of the handle 10 is a portion 29 the exterior of which has the form of an ellipse, and a portion 30 the exterior of which has the form of a circle with flattened sides 31, the circle being tangent to the ellipse at the ends of the long axis thereof and the flats being tangent to the ellipse at the ends of the short axis, with the corners of the flattened sides extending outwardly from the ellipse to form keys. The opening in the rear end of the handle 10 is provided with keys 32 similar to keys 17 in the forward end of the handle but adjoining the shoulder of the opening. To engage the magazine 13 with the handle 10, the portions 30 and 29 are thrust within the handle with the flats 31 in alignment with the keys 32, and the magazine is then turned to bring the corners of the flats behind the keys 32 and the exterior of the portion 29 at the ends of the long elliptical axis into wedge contact with the ends of the keys 32. When separated from the handle 10, the magazine 13 may be capped with a cap 33 having the same keyed form as the end of the handle.

To convert the applicator from the closed position of Fig. 1 to the ready position of Fig. 4, the telescoping member 11 is rotated within the handle 10 sufficiently to disengage the keys 17 from the keyways 18 and bring them parallel to the flattened sides of the forks 14. The member 11 is then drawn out of the handle 10 until the keys 17 are engaged by the shoulders of the flats 16 on the head 15. The instrument holder 12 is rotated to bring the shank 24 into outward extension and the nose 23 between the forks 14, the rotation being automatically limited to this position by the groove 26 and the pin 27. The member 11 is then telescoped into the handle 10 again, and rotated therein to its original position, with the keys 17 now engaging the keyways 25 as well as the keyways 13, and holding the shank 24 in substantially rigid alignment with the handle, and ready for use. To close the applicator again, the above steps are taken in the reverse order.

While I have shown and described a preferred form of my invention, it will be apparent that minor variations may be made which in no way depart from the essence or spirit of my invention, as defined in the following claims.

I claim:

1. A cosmetic applicator comprising a hollow handle, a bifurcated member telescopically slideable within said handle, an enlargement on said member imposing a limit to the inward movement thereof within said handle, a key in said handle imposing a limit on the withdrawal of said member from said handle and permitting the rotation of said member within said handle only when said member is at the said limit of its inward movement, means forming a keyway in said bifurcated member engageable with said key by the rotation of said member within said

handle for wedging said member at the said limit of its inward movement, an instrument holder pivotally mounted between the forks of said bifurcated member, and an instrument carried by said holder for applying cosmetics, said instrument holder being pivotably movable when said bifurcated member is withdrawn from said handle between a position wherein said instrument is outwardly extended from said handle and a position wherein it lies between the forks of said bifurcated member and having a handle engaging portion thereon whereby it may be enclosed with said member within said handle and held in enclosed or extended position by the wedging of said member within said handle.

2. A cosmetic applicator comprising a hollow handle, a bifurcated member telescopically slidably within said handle, an enlargement on said member imposing a limit to the inward movement of said member within said handle, a key in said handle imposing a limit on the withdrawal of said member from said handle and permitting the rotation of said member within said handle only when said member is at the said limit of its inward movement, means forming a keyway in said bifurcated member engageable with said key by the rotation of said member within said handle for wedging said member at the said limit of its inward movement, an instrument holder pivotally mounted between the forks of said bifurcated member, an instrument carried on one end of said holder for applying cosmetics, a nose on the other end of said holder adapted to engage the interior of said handle when moved therein by the inward movement of said bifurcated member, said instrument holder being pivotably movable when said bifurcated member is withdrawn from said handle between a position wherein said instrument is outwardly extended from said handle and a position wherein it lies between the forks of said bifurcated member, whereby it may be enclosed with said member within said handle and held in enclosed or extended position by the wedging of said member within said handle.

3. A support for the brush of a cosmetic applicator comprising a shank, a bifurcated member, a pivotal support for said shank between the forks of said bifurcated member, a nose in extension of said shank on the opposite side of the pivot thereof, a handle into which said bifurcated member is telescopically slidably whereby either said shank or said nose may be extended outwardly from said handle and the other contained within said handle, and cooperative keying means formed in said handle and member said keying means engageable by relative rotation of said handle and member to prevent withdrawal of said member.

4. A cosmetic applicator having in combination a handle, a member telescopically slidable within said handle, an instrument holder pivotally mounted on the outer end of said member, and an instrument carried by said holder for applying cosmetics, and locking means formed in said member, handle and holder operable by relative rotation of said member and handle to positively lock said holder with said instrument in an extended position.

5. A cosmetic applicator having in combination a handle, a bifurcated member telescopically slidable within said handle, a brush holder mounted for pivotal motion between the bifurcations of said member, a brush carried by said holder for applying cosmetics, a nose on said

holder adapted for selective engagement with said handle to prevent said pivotal motion whereby to hold said brush in extended position, and locking means in said handle and member operable by relative rotation thereof to selectively lock said holder with said nose so engaged or with said brush within said handle.

6. A cosmetic applicator having in combination a handle, a bifurcated member telescopically slidable within said handle, an instrument holder pivotally mounted between the bifurcations of said member, an instrument carried by said holder for applying cosmetics, means forming a part of said instrument holder and slidably within said handle by the inward telescopic movement of said member when the pivotal position of said holder so permits for then holding said instrument in substantially rigid outward extension from said handle, and locking means formed in said handle and member operable by relative rotation thereof to interlock the same whereby to positively hold said holder with said instrument in said rigid outward extension.

7. A cosmetic applicator having in combination a handle having a cylindrical bore, a bifurcated telescoping member telescopically slidable within said bore at one end of said handle, the forks of said member joining at their inner ends in a head fitting slidably within said bore, keys carried by said handle within said bore engageable with said head to prevent complete withdrawal thereof from said bore and engaging said forks when said member is partly withdrawn from said handle to then prevent rotation of said member, keyways in said forks engageable with said keys when said member is in its inward position to then permit partial rotation thereof and to lock said member in said inward position, said keyway being eccentric to the axis of said member and adapted thereby to enter into wedged contact with said keys to hold said member in locked position, pivotal means supported by the outer ends of said forks, an instrument holder pivotally supported by said pivotal means between said forks having a shank on one side of said pivotal means and a nose on the other side thereof, said shank and said nose being adapted to be placed alternatively between said forks or in outward extension therefrom and said nose being adapted when it is between said forks and said telescoping member is in locked position to engage said keys to hold said shank in substantially rigid outward extension, an instrument for applying cosmetics carried by said shank, and means limiting the pivotal movement of said instrument holder to an arc of one hundred and eighty degrees member.

8. A cosmetic applicator having in combination a handle having a cylindrical bore, a bifurcated telescoping member telescopically slidable within said bore at one end of said handle, the forks of said member joining at their inner ends in a head fitting slidably within said bore, keys carried by said handle within said bore engageable with said head to prevent complete withdrawal thereof from said bore and engaging said forks when said member is partly withdrawn from said handle to then prevent rotation of said member, keyways in said forks engageable with said keys when said member is in its inward position to then permit partial rotation thereof and to lock said member in said inward position, said keyway being eccentric to the axis of said member and adapted thereby to

enter into wedged contact with said keys to hold said member in locked position, pivotal means supported by the outer ends of said forks, an instrument holder pivotally supported by said pivotal means between said forks having a shank on one side of said pivotal means and a nose on the other side thereof, said shank and said nose being adapted to be placed alternatively between said forks or in outward extension therefrom and said nose being adapted when it is between said forks and said telescoping member is in locked position to engage said keys to hold said shank in substantially rigid outward extension, an instrument for applying cosmetics carried by said shank, and means limiting the pivotal movement of said instrument holder to an arc of one hundred and eighty degrees.

9. A cosmetic applicator having in combination a handle having a cylindrical bore, a bifurcated telescoping member telescopically slideable within said bore at one end of said handle, keys carried by said handle within said bore engaging the forks of said member when said member is partly withdrawn from said handle to then prevent rotation of said member, keyways in said forks engageable with said keys when said member is in its inward position to then permit partial rotation thereof and to lock said member in said inward position, said keyways being eccentric to the axis of said member and adapted thereby to enter into wedged contact with said keys to hold said member in locked position, pivotal means supported by the outer ends of said forks, an instrument holder pivotally supported by said pivotal means between said forks having 35 a shank on one side of said pivotal means and a nose on the other side thereof, said shank and said nose being adapted to be placed alternatively

between said forks or in outward extension therefrom and said nose being adapted when it is between said forks and said telescoping member is in locked position to engage said keys to hold said shank in substantially rigid outward extension, an instrument for applying cosmetics removably carried by said shank.

10. A cosmetic applicator having in combination a handle having a cylindrical bore, keys with said bore adjacent an end of said handle, a bifurcated member telescopically slideable within said handle and detachably engageable with said keys, the forks of said member joining in a head fitting slidably within said bore and engageable with said keys to prevent complete withdrawal of said member from said bore, a brush holder pivotally mounted between the outer ends of said forks, and a brush carried by said holder and placeable by the pivotal movement thereof between said forks or in outward extension therefrom, the engagement of said bifurcated member with said keys positively holding said member in its inward telescoped position and said brush in either of said placeable positions.
